UNITED STATES PATENT OFFICE.

EDWIN W. HENGER, OF WATERBURY, CONNECTICUT, ASSIGNOR TO CHASE COMPANIES, INC., OF WATERBURY, CONNECTICUT, A CORPORATION.

SEPARABLE BATHROOM BRACKET.

Application filed August 12, 1922. Serial No. 581,380.

To all whom it may concern:

Be it known that I, EDWIN W. HENGER, a citizen of the United States, residing at Waterbury, in the county of New Haven and 5 State of Connecticut, have invented a new and useful Improvement in Separable Bathroom Brackets; and I do hereby declare the following, when taken in connection with the accompanying drawings and the characters of reference marked thereon, to be a full, clear, and exact description of the same, and which said drawings constitute part of this application, and represent, in—

Fig. 1, a view in front elevation of my 15 improved separable bracket shown by broken lines as mounting a glass-receiving cup and a soap-tray.

Fig. 2, a view thereof in side elevation.

Fig. 3, a view in transverse section on the 20 line 3—3 of Fig. 1.

Fig. 4, a view, partly in side elevation and partly in section, of the upper bracket-member as segregated for separate use.

Fig. 5, a corresponding view of the lower 25 bracket-member.

My invention relates to an improvement in bath-room brackets, the object being to produce a simple and convenient two-part bracket constructed with particular reference to ease and convenience of manufacture and finish, and to having its upper and lower bracket-members adapted to be segregated and used independently of each other, if desired.

With these ends in view, my invention 35 consists in a separable bath-room bracket having certain details of construction as will be hereinafter described and particularly pointed out in the claims.

In carrying out my invention, as herein 40 shown, I produce a two-part separable bath-room bracket consisting of an upper member 6 and a lower member 7, each flared at its outer end, as at 8, to provide a horizontal seat 9 threaded and countersunk, as at 10, for the reception of a screw, by means of which any desired fitting may be fastened in place, such as a glass-receiving cup 11 and a soap-tray 12, as shown by broken 45 lines in Figure 1. An integral mounting-flange 13, formed at the inner end of the lower bracket-member 7, is formed with two countersunk screw-holes 14, but chiefly characterized by having an extended or outer 50 flat bearing-face 15 set back of a concaved

assembling-shoulder 16 in the upper face of the inner end of the main shank of the said bracket-member, as clearly shown in Figures 2 and 5. The integral mounting-flange 17, at the inner end of the shank of 60 the upper bracket-member 6, is formed with countersunk screw-holes 18, registering with the screw-holes 14 aforesaid, while the flat inner or bearing-face 19 of the said flange 17 is adapted in size and contour to fit over 65 the exposed bearing-face 15 and concaved assembling-shoulder 16 of the lower bracket-member 7, the lower end of the flange 17 being rounded, as at 20, to fit into the shoulder 16, so that, when the upper and 70 lower members are used together, their lines will merge into each other and have the appearance and effect of a unitary article, as shown particularly in Figure 2. But the special forms of the mounting-flanges 75 15 and 17 of the respective members 6 and 7 in nowise disfigure the same, so as to prevent their segregation and separate use, as shown by Figures 4 and 5 respectively, in which the mounting-screws 21 are passed directly 80 through the screw-holes of their flanges, whereas, when the two members are used conjointly, the flange 17 of the upper member fits into and overlaps the flange 15 of the lower member and clamps the latter in 85 place, between itself and the wall.

My improved bath-room bracket as thus 90 constructed provides the jobber and purchaser with an item capable of three independent uses, in each of which it will present the appearance of being complete and unitary. Thus, the two bracket-members may be used together with the effect of a duplex bracket, while either of them may be used independently without any sense of 95 being adapted for duplex use. Furthermore, by making the bracket in two parts, the machining, threading and counterboring of their outer ends is greatly facilitated.

I claim:

1. A separable, two-part, bath-room bracket, having an upper and a lower member, each adapted at its outer end for the attachment of a bath-room fixture, and each 105 having its inner end provided with a mounting-flange, the said flanges having registering screw-holes and flat, rear bearing-faces, and one being shaped to partially overlap and fit into the other, which is cor- 110

respondingly recessed, whereby the said members may be used conjointly or independently as desired.

2. A separable, two - part bath - room bracket, having an upper and a lower member, each adapted at its outer end for the attachment of a bath - room fixture, and each having its inner end provided with a mounting-flange, the said flanges having registering-screw-holes and flat, rear bearing-faces and the lower portion of the flange of the upper member being adapted to overlap and fit into the recessed upper portion of the

flange of the lower member, the flange of which is set back from the butt end of its shank to form a shoulder which is fitted by the lower edge of the flange of the upper member, whereby the said members may be used conjointly or independently as desired.

In testimony whereof, I have signed this specification in the presence of two subscribing witnesses.

EDWIN W. HENGER.
